UNITED STATES PATENT OFFICE.

WILLIAM PAUL BUTUSOV, OF TAMPA, FLORIDA.

AEROPLANE.

1,323,829.

Specification of Letters Patent.

Patented Dec. 2, 1919.

Application filed April 25, 1919. Serial No. 292,626.

To all whom it may concern:

Be it known that I, WILLIAM PAUL BUTUSOV, a citizen of the United States, and a resident of Tampa, in the county of Hillsborough and State of Florida, have invented certain new and useful Improvements in Aeroplanes, of which the following is a specification.

My invention is an improvement in aeroplanes, and has for its object to provide in an aeroplane of any character, means for preventing the machine from rocking and from skidding, means for preventing banking and skidding, and means for preventing nose dives to bring the machine back to a normal stage.

In the drawings:—

Figure 1 is a side view of the improved aeroplane,

Fig. 2 is a perspective view of the locking mechanism for the nose planes.

Fig. 3 is a plan view.

Fig. 4 is a section on the line 4—4 of Fig. 1,

Fig. 5 is a partial perspective view looking at the front.

In the present embodiment of the invention, the improved plane which may be of any usual construction, being a bi-plane in the present instance, is composed of the fuselage 1, having the upper and lower wings 2 and 3 and the usual propeller 4 arranged at the front of the planes and with its axis near the upper plane 2. The shaft 5 of the propeller is journaled just below the center of the upper plane 2 and on each side of the fuselage in front of the wings there is provided a nose plane 6. These planes 6 are secured to a common shaft 7, and they are normally held in the position shown in Fig. 1 by means of counter-weights 8, the said counter-weights being connected to the plane frames by hangers 9.

A rod 10 is hinged to a plate 11 forming a part of the fuselage between the planes 6 and below the same, as indicated at 12, and this rod is connected to the shaft 7 as shown in Fig. 2 by means of a latch 13. The upper end of the rod carries a ball or weight 14, and between the ball and the latch 13 the rod passes through a slot 15 in a rod 16 extending longitudinally of the fuselage.

It will be noticed that the shaft 7 has

a flattened portion at the latch 13, and that the latch has arms for engaging the flattened portion above and below the shaft. When the rod is swung forwardly away from the shaft, the latch will be released, permitting the nose planes to move, while when the latch is in the position of Fig. 2, the shaft is locked from movement. The rod may be operated by the bar or rod 16.

A stabilizing fin 17 is arranged between the planes 2 and 3 and the rudder post 18, the said fin being vertical, and being at the center of the fuselage. The vertical rudder 19 is connected to the post 18 as shown, and horizontal rudders 20 are arranged at the opposite sides of the vertical rudder.

Banking planes 21 are provided at the ends of the planes 2 and 3, the said banking planes being arranged in inclined position between the planes 2 and 3. Referring to Fig. 5, it will be noticed that the banking planes incline outwardly toward their upper ends. The inclination of the banking planes is 45° and these planes are stationary.

The nose or dipping planes are on each side of the cock-pit, and they are normally locked, but will release automatically, to prevent nose dive and to bring the machine back to a normal state, after which the planes will lock with the lock bar or rod 16 which is in front of the operator.

The banking planes 21 will prevent banking or skidding, what is designated as "going off on the wing". The stabilizing fin extending from the main plane to the rudder, prevents the machine from rocking and from skidding. While the improvement is shown applied to one form of flying machine, it will be understood that it may be applied to any form with equal facility.

I claim:—

1. In a flying machine, the combination with the fuselage, the main supporting planes and the rudder, of banking planes arranged between the main planes at the ends thereof in inclined position, a stabilizing fin extending between the main planes and the rudder in vertical position, and nose planes at the front of the fuselage on each side thereof, and counterweighted to hold normally a predetermined position, and means for locking the nose planes against movement.

2. In a flying machine, the combination with the fuselage, the main supporting planes and the rudder, of banking planes arranged between the main planes at the ends thereof in inclined position, a stabilizing fin extending between the main planes and the rudder is vertical position, and nose

planes at the front of the fuselage on each side thereof and counterweighted to hold normally a predetermined position.

WILLIAM PAUL BUTUSOV.
